UNITED STATES PATENT OFFICE.

JOHN G. WOLFE, OF CHICAGO, ILLINOIS.

DESIGN FOR AN AUTOMOBILE TIRE.

Application filed April 3, 1922. Serial No. 1,512. Term of patent 14 years.

To all whom it may concern:

Be it known that I, JOHN G. WOLFE, a citizen of the United States, residing at Chicago, in the county of Cook and State of Illinois, have invented a new, original, and ornamental Design for Automobile Tire, of which the following is the specification, reference being had to the accompanying drawing, forming a part thereof.

Fig. 1 shows a plan view of a portion of the tread surface of the automobile tire embodying this invention, and

Fig. 2 is a partial side elevation of the tire.

I claim:

The ornamental design for an automobile tire, as shown.

JOHN G. WOLFE.
